DESIGN FOR A WOODWORKING TOOL

Alonzo M. Dunn, Perryton, Tex.

Application August 31, 1934, Serial No. 53,123

Term of patent 3½ years

To all whom it may concern:

Be it known that I, ALONZO M. DUNN, a citizen of the United States, residing at Perryton, in the county of Ochiltree and State of Texas, have invented a new, original, and ornamental Design for a Woodworking Tool, of which the following is a specification, reference being had to the accompanying drawing, forming part thereof.

Figure 1 is a side elevational view of the wood-working tool, showing my new design.

Figure 2 is a top plan view of Figure 1.

Figure 3 is a bottom plan view of Figure 1.

Figure 4 is an elevational view of the left hand end of Figure 1.

Figure 5 is an elevational view of the right hand end of Figure 1.

I claim:—

The ornamental design for a woodworking tool, as shown.

ALONZO M. DUNN.
